(57) **CLAIM**

The ornamental design for a mount for defibrillator paddles,
as shown and described.

DESCRIPTION

FIG. 1 is a perspective view of a mount for defibrillator paddles according to an aspect of the present disclosure; FIG. 2 is a front elevation view thereof;

FIG. 3 is a top plan view thereof;

FIG. 4 is a right side elevation view thereof;

FIG. 5 is a left side elevation view thereof;

FIG. 6 is a rear elevation view thereof;

FIG. 7 is a bottom plan view thereof; and,

FIG. 8 is another perspective view of the mount for defibrillator paddles, shown in a position of use, where the paddles are mounted.

The broken lines in the drawings illustrate portions of the mount for defibrillator paddles and its environment, which form no part of the claimed design.

1 Claim, 8 Drawing Sheets
